UNITED STATES PATENT OFFICE.

DAN READ, OF BOSTON, MASSACHUSETTS, ASSIGNOR TO A. A. TAYLOR, OF SAME PLACE.

IMPROVEMENT IN COVERING SPINNING-ROLLS.

Specification forming part of Letters Patent No. 36,257, dated August 19, 1862.

To all whom it may concern:

Be it known that I, DAN READ, of Boston, in the county of Suffolk and Commonwealth of Massachusetts, have invented a new and improved spinning-roll to be used upon spinning-frames, drawing-frames, and other machinery used in mills for the manufacture of cotton and other fibrous material; and I do hereby declare that the following is a full and exact description thereof, reference being had to the accompanying drawings, and to the letters of reference marked thereon.

The nature of my invention consists in the different manner in which my roll is constructed from all other rolls used for the same purpose.

My roll is constructed and composed partly of india-rubber and partly of iron, (or other metallic substance,) using iron only in so far as is necessary to strength and to the use designed, and making the roll itself, so far as may be, of india-rubber. The part which consists of iron is the bearings, one at each end and one in the center, (or a bearing at each end only, as the case may be;) also two flanges between every two bearings, which flanges confine the india-rubber, holding the same firmly as a component part of said roll; also a central shaft connecting the flanges for the purpose of giving sufficient strength to the roll that it may bear the weight and pressure put upon it, (said bearing, flanges, and shafts may be of separate pieces, or they may be formed or cast in one solid piece;) also the india-rubber composing the important part of my roll confined between the said flanges. The roll after being thus constructed, the mode of which construction is described hereinafter, is vulcanized in the part composed of india-rubber, in the usual manner, by a heat of 270° Fahrenheit, or thereabout, as may be required. I have used different kinds of india-rubber or india-rubber compounds in forming this roll, and do not pretend to claim that there is any special compound of such as are prepared or made for vulcanization that is better than another; but that there is a difference, and that several of them answer my purpose, more particularly those when vulcanized after the roll is constructed, producing a hard compact outer surface or circumference. The hard outer surface

or circumference, combined with an elasticity of the inside, by being vulcanized, as aforesaid, after the roll has been constructed, makes a spinning-roll superior to any other with which I am acquainted or of which I have any knowledge.

The form of roll selected to illustrate by drawings of the same is the roll from the cotton-spinning frame, and in common use, having three bearings, one at each end and one in the center.

Figure 1 represents the spinning-roll as formed and completed by the combination of the aforesaid iron bearings, flanges, shafts, and india-rubber, and showing, also, the end and center bearings. Fig. 2 represents a section of one-half of said rolls, showing these component parts—viz., the bearings at the end, the flanges *m m*, the shaft *g h*, by which said flanges are connected, and the india-rubber *e f g h*; also, Fig. 3 represents a section of one-half of said roll, showing that part of the roll composed of iron only, (or other material suited to the same purpose)—viz., the bearings at the end, flanges *m m*, the central shaft, *k l i g*, connecting said flanges, also showing the space occupied by the india-rubber composing the important part of my roll. The dotted line *i j* and corresponding one *k l* show the form of the iron roll in common use before being covered for use.

The difficulties heretofore in making india-rubber to serve the purpose of a surface to spinning-rolls has been the tendency of the fibrous material passing under the roll to wear grooves in the surface of the same, and thereby preventing the proper and desired action of the roll upon the said fibrous material, and also the action of oil upon the said india-rubber; but my mode of constructing a roll, such as aforesaid, having an india-rubber surface—hard and compact—with the desired smoothness, makes a roll which with the same gears will spin a finer yarn and more even than the roll in common use, resisting at the same time the action of oil and the formation of grooves upon the surface by use, while the inside possesses that desirable degree of elasticity by which the roll becomes more solid as the pressure upon the roll is made heavier; also by the same elastic quality resisting wear and tear,

and possessing also the valuable quality of endurance, wearing longer without repair than rolls in common use covered with cloth and leather.

I construct said roll by spreading said india-rubber or compound, as aforesaid, in a semi-fluid state upon strips of cloth, (of cotton, linen, or other description,) and winding the same, one layer over another, upon the said shaft, connecting said flanges aforesaid, until the thickness of the india-rubber (combined with the cloth) rises above the circumference of the flanges, as seen at Fig. 1, *a b c d*, vulcanizing said roll in the part composed of india-rubber in the common mode of vulcanizing, and to the temper of elasticity and hardness of outer surface, as aforesaid. Ordinarily the surface obtained after the roll has been vulcanized is sufficiently smooth and uniform for the coarser kinds of spinning; but if from any defect in constructing and vulcanizing the roll it should not have a circumference sufficiently smooth, or should said roll be required for the finer kinds of spinning, in such cases the roll may receive an additional finish by being placed in a lathe and turned to the smoothness desired. The first cost (or repair) of this roll being no more than the ordinary rolls of iron covered with cloth and leather, a saving is effected in the expense of manufacturing yarns from

fibrous material. This mode of constructing the spinning-roll dispenses with the necessity to cover the roll with cloth and leather in the manner in common use, and also dispenses with the covering of such rolls with any shells or hollow cylinders of vulcanized india-rubber; but produces in its construction, as aforesaid, a roll not wanting any covering, but complete in itself for the uses designed.

My claim is confined to the mode of construction and combination of the two materials of which the roll may be composed, as aforesaid.

What I claim as my invention, and desire to secure by Letters Patent, is—

The construction of a spinning-roll by the combination in solid form of india-rubber with iron or other metal, and in said solid form vulcanized in the part composed of said india-rubber, as herein described; also the obtaining by the aforesaid means the harder and compact outer surface combined with an inner elasticity possessing the advantages aforesaid, and such other rolls as are substantially of the same construction claiming to produce the same improvements.

DAN READ.
